UNITED STATES PATENT OFFICE.

FREDERICK HENRY KREBS, OF FREDERIKSBERG, NEAR COPENHAGEN, DENMARK.

DEVICE FOR ATTACHMENT OF ELECTRIC CONDUCTORS TO INSULATORS.

1,346,128.

Specification of Letters Patent.

Patented July 13, 1920.

Application filed June 4, 1919. Serial No. 301,747.

To all whom it may concern:

Be it known that I, FREDERICK HENRY KREBS, electrical engineer, citizen of the Kingdom of Denmark, residing at Frederiksberg, near Copenhagen, Denmark, have invented new and useful Improvements in Devices for Attachment of Electric Conductors to Insulators, of which the following is a specification.

10 The present invention has for its object a device for attachment of electrical conductors and the like to insulators or other supports.

15 The invention is illustrated on the drawing, where—

Figure 1 shows a fragmentary side elevation of my invention;

Fig. 2 shows a fragmentary side elevation of a modification,

20 Figs. 3 and 4 show a similar view of another modification,

Fig. 5 shows a similar view of a still further modification, and

25 Figs. 6 and 7 details of the structure shown in Fig. 5.

Heretofore the fastening of an electrical conductor to an insulator has mainly been effected by the so-called "bindings." These are made of suitable wires tied on, by casual workmen—more rarely by really skilled erectors—as single or double cross-windings. Use has also been made of clips partly formed before being placed in position. The placing of such clips requires the use of 30 tools, however, in order to complete the forming of the clips in the field. The consequence of these working processes is that many bindings are not made with sufficient care, and the conductor is frequently exposed to damage, which drawback becomes 40 most serious as an efficient inspection of each single binding is practically impossible. Sources of faults in the net will easily be the result hereof.

45 In order to avoid these drawbacks, use may be made of the device specified in the following, all parts being previously adjusted in the shop and being adapted to be securely erected by unskilled workmen, 50 without the latter having to touch the conductor with any tool. The further advantage is attained that any subsequent undoing of the bindings, for instance for the purpose of tightening or renewing the conductor, 55 will be easy to perform.

In Fig. 1 there is shown one form of my

fastening device. A one strap-half 23 is here hoop-shaped and is fitted, at one end, with a bearing 28 for an intermediate link 25, whereto the other band 24 is attached, 60 while the link 25 is occupying the position 25'.

When the link 25 is turned away from the position 25', a lug 30 on the link 25 lifts the latter slightly from its seat in the bearing 65 28. Being actuated by the tension in the hoops 23 and 24, the link will again sink somewhat during the last portion of its rotation and will therefore be held in the position 25. By inserting the hoop 23 more 70 or less deeply in the notch 29 of the link 25, when the said link occupies the position 25', the length of the hoop 23 may be adjusted in such a manner that the proper tensions 75 are attained in each individual case.

In Fig. 2, 51 is the insulator, 53 and 54 the strap-halves and 55 the intermediate link consisting of a stamped plate whose one end 56 rests in a bearing 58 made in one with the strap-half 53, while the strap-half 54 80 is shaped as a loop whose ends 59 are hook-shaped and are hooked into holes 60 in the intermediate link 55. The bearing surface of the bearing 58 is curved in such a manner that the link 55, while being moved out 85 from the position 55', causes the not shown conductor to be gradually pulled toward the insulator 51 and then toward the link's extreme position 55' shown by dotted lines, the conductor being allowed to recede only to 90 the slightest possible extent. Hereby the result is attained that the erection is rendered easier, and also that the proper tensions in the individual parts are secured.

If several holes 60 are provided, the length 95 of the device may be altered whereby for instance differences in the insulator diameters may be equalized, and the tensions may be varied.

In Fig. 3, 71 is the insulator and 73, 74 100 the clip-halves. The part 73 consists of a heavy flexible wire whose one end is fastened by soldering, welding, riveting or upsetting to a stout cast or pressed hook 76 (catcher), while the other part 74 is fastened to a body 79 fitted with a bearing 78. The bearing 78 is of similar shape as the bearing 58 in Fig. 2. 75 is the intermediate link which is fitted with a rivet 80 serving as fulcrum for the intermediate link turning and moving in the bearing 78. The link 75 is further fitted with notches 81

wherein the loop 74 may be hooked. The strap-part 74 is constructed, like the strap-part 73 as a loop with a catcher 77.

In placing the conductor it is of great importance to have it fastened in such a manner that it cannot later on slide on the insulator, as this has a wearing effect on the wire and on the insulator as well. Care must also be taken to prevent the wire from becoming detached in case of rupture between two poles, and the clip arrangement with the intermediate member should therefore be constructed with this case in view. The very bending of the conductor 72, 15 along the insulator, as produced by the tightening device, tends strongly to prevent such longitudinal movement, which may be further prevented by the catchers 76 and 77 being shaped in such a manner that they 20 prevent the wire from sliding through these catchers. For instance the catchers 76, 77 in Fig. 3 may be shaped in such a manner, Fig. 4, that the wire becomes pinched therein, whereby the wire is prevented from sliding in the hook. This may be carried out 25 for instance by the notch 82 being made wedge-shaped.

If the catchers 76, 77 for instance are further fitted with lugs or noses 86, 87, the result is attained that if the conductor 72 breaks close to the insulator, the bend will partly be maintained by the catcher, as the noses will prevent the conductor 72 from being straightened out in the catcher where- 30 by the wire is further secured in the same.

In Fig. 5, 91 is the insulator and 93, 94 are the clip-halves. While the member 94 is shaped as a loop (Fig. 7), the member 93 may, for instance, be drop-forged or 35 stamped from a suitably shaped plate (Fig. 6), and is fitted, at 96, with a hook and is connected with a member 98 shaped as a bearing, wherein the pin 100 of the intermediate member 95 may move. The intermediate member 95, as shown, is fitted with 40 holes 101 wherein the hook-shaped ends 104 of the loop 94 are inserted and come into contact with one another in such a manner (Fig. 7) that a subsequent straightening out of the hooks in consequence of 45 the tensile forces will be prevented. A wrench 105 is used for placing the device in position, especially for turning the intermediate link. The bearing 98 may be 50 fitted with a hole 108 for a suitable bolt, in order to provide an electrically conductive connection with a branch-wire or turnout.

In order to protect the conductor 102, for 55 instance where metals of different hardness come in contact with one another, there may for instance be inserted linings 106, 107 of suitable shape and material between the hook 96 and the bearing surface 97 of the 60 loop.

In order to be able to use the same tightening device for several wire diameters, insulator dimensions and the like, the individual parts of the fastening device are adjusted at the factory and stamped with information in that respect. The loop-parts, for instance, may be given the lengths corresponding to the standard diameters of insulators. A final adjustment may be performed during the erection, for instance the 65 band-shaped member 26 in Fig. 1 may be shortened, as mentioned above, by the insertion of the hook 29 in the lever 25, and the length of the intermediate link in Figs. 2, 3, 5 may be adjusted by the provision of 70 several holes or notches wherein the loop 75 may be inserted.

Experience has demonstrated the great importance of the fastening device fitting well against the insulator along the largest 75 possible portion of the circumference of the same. The insulators, even of the same make and pattern, not being entirely alike, however, the lengths must be varied, for instance in the manner mentioned above, 80 but care must also be taken for the strap-parts proper to be bent into contact with the insulator for the longest possible distances when actuated by the tensions produced by the erection. It is important, for 85 instance, that the strap-parts in Fig. 2 at the portions with notation marks 53, 54, and in Fig. 3 at the portions 73, 74, as well as in Fig. 5 at the portions 93, 94, should fit closely against the insulators, and for 90 that reason the strap-parts are given such 95 shape and profile that bending or fitting is facilitated, and a reliable contact is attained.

By the devices shown, there may be attained very considerable tensions, greatly exceeding those otherwise attainable by ordinary bindings and thereby, the conductor may be immovably fastened to the insulator 100 which is of great importance for the durability of the conductor as well as of the insulator.

The intermediate link 75 (95) may be constructed in such a manner that it may be removed after the straps 73 and 74 (93 115 and 94) have been tightened about the insulator, the said intermediate link being then constructed in such a manner that the straps 74 (94), after being tightened, slides out from the intermediate link and down on a hook or a notch in the bearing-shaped member 78 (98), whereafter the intermediate link is removed.

By suitable selection of the shape of the curved bearing surface between the link-members 55—58, 75—78 and 95—98, the necessary power to be applied in mounting the device may be reduced to a minimum.

Having now particularly described and ascertained the nature of my said invention 120

and the manner in which the same is to be performed, I declare that what I claim is:—

1. A device for attaching line wires to insulators comprising a pair of bands located, one on either side of the insulator and having ends engaging the line wire at spaced intervals, and means for forcing the free ends of the bands toward each other comprising means permitting the slackening of the bands during the forcing operation. 60
  2. A device for attaching line wires to insulators comprising a pair of bands located one on either side of the insulators and having ends engaging the line wire at spaced intervals and means, comprising a member, one end of which is loosely pivoted in one of said bands, for forcing the free ends of the bands toward each other. 65
  3. A device for attaching line wires to insulators comprising a pair of bands located one on either side of the insulator and having ends engaging the line wire at spaced intervals and means for forcing the free ends of the bands toward each other, said means being a hinge, comprising a bearing member, connected to the free end of one of the bands, and a link, being attached to the free end of the other band and journaled in the bearing member, the latter being shaped 70
  - 30 in such a manner that the link, during its rotation in the said bearing member, for the purpose of tightening the bands and the line wire about the insulator, slides in the said bearing member, at right angles to its axis 75
  - 35 of revolution therein whereby a slight retrograde and therefore slackening motion of the line wire is allowed during erection, shortly before the link has reached its final position. 80
  - 40 4. A device for attaching line wires to insulators comprising a pair of bands located one on either side of the insulator and having ends engaging the line wire at spaced intervals and means for forcing the free 85
  - 45 ends of the bands toward each other, said means being a hinge, comprising a bearing member, connected to the free end of one of the bands, and a link, being attached to the free end of the other band and journaled 90
  - 50 and free to slide in the bearing member, so that the link by being turned in the bearing member, tightens the bands and the line wire about the insulator, the said bands engaging the line wire at a spaced interval in such a 95
  - 55 manner that when they become actuated by 100
- the tensions produced by the process of erection, they will adjust themselves closely to the largest possible portion of the circumference of the groove of the insulator.
5. A device for attaching line wires to insulators comprising a pair of bands located one on either side of the insulator and having ends engaging the line wire at spaced intervals and means for forcing the free ends of the bands toward each other, said means being a hinge, comprising a bearing member, connected to the free end of one of the bands, and a link, being attached to the free end of the other band and journaled 70
- and free to slide in the bearing member, so that the link by being turned in the bearing member, tightens the bands and the line wire, which is gripped by catchers on the end of the bands, closely about the curved insulator surface, the said catchers being shaped in such a manner that they firmly grip the line wire and prevent any motion of the wire through the catchers after its securing. 75
6. A device for attaching line wires to insulators comprising a pair of bands located one on either side of the insulator and having ends engaging the line wire at spaced intervals and means for forcing the free ends of the bands toward each other, said means being a hinge, comprising a bearing member, connected to the free end of one of the bands, and a link, being attached to the free end of the other band and journaled 80
- and free to slide in the bearing member, so that the link by being turned in the bearing member, tightens the bands and the line wire, which is gripped by catchers on the end of the bands, closely about the curved insulator surface, the said catchers being shaped in such a manner that they firmly grip the line wire and prevent any motion of the wire through the catchers after its securing, there being provided, between the catchers and the line wire, linings preventing any damage of the line wire at the places where the catchers take hold of the wires. 85

In witness whereof, I have hereunto signed my name in the presence of two subscribing witnesses.

FREDERICK HENRY KREBS.
